CLARK A. THARP, OF LEAVENWORTH, KANSAS.

COPY-HOLDING STAND.

Application filed December 31, 1925. Serial No. 78,550.

My invention relates to improvements in copy holding stands. It is particularly adapted for use in connection with a typewriter for supporting the note book of a stenographer, while the latter is transcribing with the typewriter.

One of the objects of my invention is to provide a stand of the kind described with which the note book may be moved on the stand from a central position over the typewriter to positions at either side thereof, and by which the note book may be moved in either of these positions so as to face the writer using the machine with either the front or rear side of the book facing forwardly, whereby notes may be made on either side of the book, when desired.

A further object of my invention is to provide a stand of the kind described, which is simple, cheap to make, strong, durable, not liable to get out of order, which can be readily operated by an inexperienced person, and by which the note book may be moved from an elevated central position over the machine to a lowered position at the rear of and at either side of the central elevated position.

The novel features of my invention are hereinafter fully described and claimed.

In the accompanying drawing, which illustrates the preferred form of my invention,

Fig. 1 is a front elevation of my improved stand.

Fig. 2 is a side elevation, partly broken away, of the same.

Fig. 3 is an enlarged section on the line 3—3 of Fig. 2.

Fig. 4 is a perspective view, enlarged, of the U-shaped member and parts connected therewith.

Fig. 5 is an enlarged perspective of a portion of the copy holding member.

Fig. 6 is a side elevation of the copy holding member and parts connected therewith, partly broken away.

Similar reference characters designate similar parts in the different views.

The stand is provided with a copy holding member 1, of the usual type adapted to support a note book, not shown, but which is of the usual kind, and which is adapted to rest on a shelf 2 at the lower end of the member 1, and the leaves of which are adapted to be folded over the upper edge of the holder 1

after the matter on the leaves has been transcribed with the typewriter.

The stand is provided also with a supporting standard, which may comprise a relatively heavy base 3, of any suitable form, the one shown being circular, and provided with a central vertical hole 4 therethrough, and a vertical post 5, which at its lower end has a cylindrical shouldered portion 6 revolvable on a vertical axis in the hole 4, the post having a lateral projection 7 adapted to enter any one of four recesses 8 in the top of the base 3, for releasably holding the post in either of four positions to which the post may be revolved.

A right angled swinging member has one of its arms 9 pivoted on a horizontal axis to the post 5, so that the member may be swung from a central vertical position to horizontal position at opposite sides respectively of the post 5, Figs. 1 and 2, dotted lines. The other arm 10 of the right angled member extend forwardly horizontally from the arm 9. The pivoting means for connecting the arm 9 to the post 5 may be a horizontal bolt 11 which extends through the post 5 and has on it a nut 12, which bears against one side of the post, the arm 9 bearing against the other side of the post. The head of the bolt 11 bears against a spring washer 13 which bears against the arm 9 and exerts a yielding frictional bearing for releasably holding the arm 9 in the position to which it may be moved.

The copy holding member 1 is provided near its lower end and on its rear side with a tubular stem 14, Figs. 2, 5 and 6, adapted to receive the split cylindrical end of a member 15, the other end of which is provided with a head which is revolvable in all directions in two holes 16 respectively provided in the arms 17 of a U-shaped member, pivoted to the arm 10 on an axis at right angles to the bolt 11, by means of a bolt 18 which extends through a washer 19, which rests on the arcuate end of the U-shaped member, the bolt also extending through the arm 10, and having mounted on it a nut 20 which bears against said arm 10, Figs. 3 and 4. This construction affords a spring clamping connection between the U-shaped member and the arm 10, whereby the U-shaped member is reliably releasably held in the position to which it is adjusted. A bolt 21 extends through the arms 17, its head bearing

against one arm, and a nut 22 on the bolt 21 bearing against the other arm 17, for holding the arms 17 from spreading. The head of the member 15 is, preferably, spherical so as to afford a universal joint connection between the U-shaped member 17 and the copy holding member 1.

The right angled member, the U-shaped member and the member 15 serve as a universal joint connection between the standard and the copy holding member 1, whereby the latter may be swung from the upright central position, shown in Figs. 1 and 2 in solid lines, to the dotted positions at opposite sides respectively of the central position, as shown in dotted lines in Fig. 1. This universal joint connection also enables the copy holding member 1 to be moved, in either of the positions named, so as to incline upwardly and rearwardly, and with either the rear or front side facing forwardly, as shown in Figs. 2 and 6, the position in which the rear side faces forwardly being shown in dotted lines in said figures.

In the operation of the stand, to move the copy holding member from the central position shown in solid lines in Figs. 1 and 2, to the side position shown in dotted lines in said figures, the right angled member is swung to the right or left, as desired; to the horizontal position, and the member 1 and member 15 are swung in the arms 17 so that the member 1 will be upright and inclining upwardly and rearwardly. The members 1 and 15 may then be swung on a vertical axis so that the copy holding member will face the writer.

If when in the side position, the writer desires to make notes on the rear side of the note book, the member 1 is swung forwardly and downwardly from the position shown in solid lines, Fig. 6, to the position shown in dotted lines in said figure.

If it is desired, when the member 1 is in the central position, shown in solid lines in Fig. 2, to make notes on the rear side of the note book, the U-shaped member is revolved to a position diametrically opposite to that shown in solid lines in Fig. 2, and the member 15 and with it the member 1 are swung

rearwardly on the U-shaped member 17 to the position shown in dotted lines in Fig. 2, in which position, the rear side of the member 1, and that of the note book thereon, will incline upwardly and rearwardly and facing forwardly, so that notes may be readily entered on the rear side of the note book.

When it is desired to revolve the right angled member 9—10 so that the copy holder is at one side and at the rear of the usual operative positions above described, the post 5 is lifted to release the projection 7 from the base 3, upon which the post 5 and right angled member may be revolved on a vertical axis until the projection 7 enters one of the other recesses 8, when the post is lowered so that the projection 7 will enter such recess, thereby holding the post in the adjusted position.

I do not limit my invention to the structure shown and described, as many modifications, within the scope of the appended claims, may be made without departing from the spirit of my invention.

What I claim is:—

1. In a copy holding stand, a standard, a right angled member pivoted thereto on a horizontal axis by means of one of its arms, a U-shaped member pivoted to the other arm of said right angled member on an axis at right angles to the latter, a copy holding member, and a member supporting said copy holding member and supported by and having universal joint connection with the arms of said U-shaped member.

2. In a copy holding stand, a standard comprising a base and a post revolvable thereon on a vertical axis, a right angled member having one of its arms pivoted on a horizontal axis to said post, a U-shaped member pivoted to the other arm of said right angled member on an axis at right angles to the axis of the latter, a copy holding member, and a member supporting said copy holding member and supported by and having universal joint connection with the arms of said U-shaped member.

In testimony whereof I have signed my name to this specification.

CLARK A. THARP.
